UNITED STATES PATENT OFFICE.

HERMAN GARRISON, OF CHICAGO, ILLINOIS.

CAN OPENER.

Application filed April 13, 1927. Serial No. 183,271.

The object of this invention is to make certain improvements designed to facilitate the use of a longer knife than is at present employed in that type of can opener which is in most general use, and which comprises a handle, a stock fitted to it and modified at the end to form a guiding fulcrum, and a downwardly offset uppercut knife extending far enough beyond the fulcrum to permit the point to be inserted into the can.

Fig. 1 is a side view, showing the stock A fitted with a handle, and knife B riveted to the stock. The cutting edges are indicated by double lines, a lower cutting edge being essential to the introduction of the lengthened knife into the can.

Fig. 2 is a partial top plan view, showing the knife B curved in conformity to the contour of a circular can, and having a reverse curve at H; also the strip metal stock bent aside to form the fulcrum member D.

Fig. 3 shows the front face of the fulcrum member D, and the recess E by which the guiding fulcrum is formed.

Fig. 4 will be employed to illustrate the disadvantage of using a knife of too great curvature.

Figs. 5 and 6 will be of use in explaining the method by which a knife of given curvature is adapted to a can of greater curvature.

Figs. 7, 8 and 9 will be used to explain a structural detail designed to make the successive kerfs continuous and thus prevent the formation of a jagged edge.

On account of the increase in the length of the knife, the process of insertion requires the use of a longer projection beyond the fulcrum than in the ordinary can opener of this type, a fact which involves us in a difficulty with regard to the terminal part of the knife. It is this feature of construction with which this application is particularly concerned.

It is evident that the lengthened knife must be curved if it is to be used on circular cans, and we must determine what curvature will be best adapted to cans of various diameters.

We shall find it wholly impracticable to use a knife having the curvature of a small can. One principal difficulty met with is illustrated by Fig. 4, which shows in section a knife with a curvature adapted to a can three inches in diameter, with its point in a vertical position about to pierce a horizontal surface. Since this knife must be

attached to the stock at its base, it will be seen that the power applied by direct pressure will be in line with the arrow F, but the force that produces penetration must act in the direction of the arrow G, with the consequent loss of a large component, the larger part in fact, of the direct pressure.

We will, therefore, adapt the knife to the curvature of a large can and show certain modifications which will make it fit a small can.

Fig. 5 shows a partial circumference of a can 3 inches in diameter, and section of knife which is adapted to a can 5 inches in diameter. P indicates the point at which the knife passes under the fulcrum. It is apparent that P is too far from the rim to permit a satisfactory adjustment of the fulcrum to the crimp. We must move the point P close to the rim. The simplest way to do this is to bend the knife in such a manner that its top plan view is represented by Fig. 6. This arrangement, however, will lead to the same difficulty that was illustrated by Fig. 4.

To avoid this, I employ a reverse curve as shown at H in Fig. 2, giving to the point practically the same direction as before.

Still another difficulty in operation arising from the use of the reverse curve is that at the completion of a kerf an additional lateral cut is made by the transverse part of the knife, T—H, Fig. 2, as shown at V, Fig. 7. When the ensuing kerf is completed and the operator undertakes to move the knife into position for the next one, it catches the projecting point at V and its operation is thereby impeded. I therefore discontinue the cutting edge at T, Fig. 2, where the jog begins.

This result may be accomplished in two ways; either by a break in the contour of the edge, as shown in Fig. 8, or by substituting a blunt margin for the cutting edge 100 beyond the point T, as shown in Fig. 9.

As to the method of operating this opener, it will be seen that when the knife is to be introduced into the can the reverse curve will make it somewhat difficult to push the 105 blade downward and forward. It is readily introduced by prying it backward, the upper margin of the part which projects beyond the guiding fulcrum being used as a fulcrum for that purpose, after penetration has 110 been effected.

The blunting of the anterior part of the

margin, illustrated by Fig. 9, will add to the efficiency of this fulcrum, which acts against the lower surface of the top of the can.

5 I claim:

1. A can opener in the form of a lever of the second class, having a guiding fulcrum formed by a recess at the end of a handled stock, and a downwardly offset uppercut

10 knife secured to the stock and extending forward past the guiding fulcrum; said knife being laterally curved in the direction of its length and provided with an additional cutting edge on its lower margin; that portion

15 of said knife which projects past the end of the fulcrum-bearing stock being laterally offset by a curved jog, the direction of displacement of the offset portion being toward that side of the instrument on which lies the

20 center of curvature of the directional curve of the knife; and the upper cutting edge being forwardly interrupted by a recess in the contour of the upper margin of the

25 knife, said recess being located approximately at the beginning of the above mentioned curved jog.

2. A can opener in the form of a lever of the second class, having a guiding fulcrum formed by a recess at the end of a handled stock, and a downwardly offset uppercut 30 knife secured to the stock and extending forward past the guiding fulcrum; said knife being laterally curved in the direction of its length and provided with an additional cutting edge on its lower margin; that por-

tion of said knife which projects past the end of the fulcrum-bearing stock being laterally offset by a curved jog, the direction of displacement of the offset portion being toward that side of the instrument on which 40 lies the center of curvature of the directional curve of the knife, and the upper cutting edge being forwardly discontinued at a point located approximately at the beginning of the above-mentioned curved jog and 45 being thence succeeded by a blunt upper margin.

3. A can opener in the form of a lever of the second class, having a guiding fulcrum formed by a recess at the end of a handled 50 stock, and a downwardly offset uppercut knife secured to the stock and extending forward past the guiding fulcrum; said knife being laterally curved in the direction of its length and provided with an additional cutting edge on its lower margin; that portion 55 of said knife which projects past the end of the fulcrum-bearing stock being laterally offset by a curved jog; the direction of displacement of the offset portion being toward 60 that side of the instrument on which lies the center of curvature of the directional curve of the knife; and a portion of the upper edge, located on that part of said knife which connects the offset portion with the 65 main body of the knife, being made blunt, and of a greater thickness than that part of the upper edge which extends rearwardly from the above mentioned curved jog.

HERMAN GARRISON.
